STRAIGHT LIFT PUMPING UNIT

Christopher G. Hopkins, Nashville, Tenn.

Application February 16, 1937, Serial No. 126,058

11 Claims. (Cl. 74—103)

This invention relates to lift pumps for pumping oil, gas and analogous uses, and is particularly concerned with pumps generally classed as of the walking beam straight line lift type.

Various types of linkage mechanism have been devised for imparting a supposedly straight line movement to the polish rod of a lift pump, or for converting the arcuate movement of the walking beam into rectilinear movement. There are certain objectionable features to known mechanisms of this type. The linkage mechanism is not only complicated in most instances, but actual experience shows that the supposedly rectilinear movement is not in fact true, and that the polish rod is being wobbled or slightly bent during the pumping operation. This may not be in evidence until after the pump has been in use for some time, but eventually it shows up through wear on the polish rod and bearings and looseness of the coating parts. In a number of instances, the complicated system of linkage mechanism is not sufficiently rigid and strong to give the desired life to the pumping unit.

The primary object of the invention, therefore, is to provide a pumping unit of the straight line lift type wherein the arcuate movement imparted to the walking beam is converted into true rectilinear movement, thereby giving a true straight line action to the polish rod, and to accomplish this desired result with mechanism of a simplified type.

Another object is to provide a straight line lift pump unit wherein the mechanism for converting arcuate into straight line motion is not only of a simplified type but embodies relatively great strength and is capable of long life with a minimum of wear on the coating parts.

Another object of the invention is to provide a straight line lift pump unit embodying a particularly advantageous type of straight line toggle linkage mechanism which in addition to imparting a true straight line movement to the polish rod serves to brace the walking beam against a tendency toward rotation in a horizontal plane.

The foregoing and other objects and advantages will become apparent in view of the following description taken in conjunction with the drawing, wherein:

Fig. 1 is a view in side elevation of a lift pump embodying the features of the present invention.

Figs. 2 and 3 are, respectively, horizontal and vertical sectional views taken substantially on the lines 2—2 and 3—3 of Fig. 1.

Fig. 4 is a diagrammatic representation of the action of the improved lift pump.

Generally speaking, the unit consists of a main stationary frame structure herein termed a main or stationary Samson post having mounted on the upper extremity thereof an arcuately movable Samson post by means of which the walking or rocking beam is given a floating mounting. The movable Samson post and walking beam have connected thereto a particular arrangement of toggle linkage whereby the conversion of rotary into straight line movement is carried out.

Referring in detail to the drawing, the numeral 5 indicates a base on which is disposed the stationary frame structure or main Samson post, generally indicated at 6. As shown the stationary Samson post is made up of skeleton framework, and at the upper extremity thereof the framework is extended horizontally outward. To provide for this extension, side beams 7 are rigidly connected to the upper end of the framework 6 and converge inwardly, as at 7a; and at their ends are constructed to provide a link shaft bearing as at 8.

Approximately in the axially central portion of the Samson post 6 is mounted a supplemental Samson post or beam supporting member 9, which at its lower end is pivotally supported on a shaft 10. A rocking or walking beam 11 is pivotally mounted on the upper end of the movable post 9 through the medium of a bearing block or shoe 11a. Since the post 9 is permitted to swing arcuately on shaft 10 and since the beam 11 is permitted a like movement on said post, the beam is given a floating support or mounting on the main stationary Samson post or framework 6.

At one end said beam is provided with a bearing bracket 12 which is pivotally connected to the polish or lift rod 13 of a well pump, the latter not being shown in the drawing since its particular construction forms no part of the present invention. At its opposite end, the beam 11 is operatively connected with a drive unit 14 through the medium of a connecting rod 15.

Toggle mechanism comprising horizontal links 16, 17 and vertical link 18 is provided. Links 16 are pivotally connected at one end to the post 9 through the medium of a shaft 19 and at the opposite end thereof to the link 17 through the medium of a shaft 20. Link 17 at its outer end is pivotally anchored to the frame extension 7a through the medium of the member 8. Link 18 at its upper end is provided with a pivoted bearing block 21 which is secured to the walking beam 11, and at its lower end has bearing on shaft 20.

the latter serving as a common connection for the inner ends of the respective links.

In operation, assuming that the first movement of the connecting rod 15 will be an upward thrust 5 from the position shown in Fig. 1 and that the polish rod is to be given a downward stroke. The thrust of the connecting rod 15 will have a tendency to move the stroke end of beam 11 arcuately, but this tendency is resisted by the links 16 and 17 which at this time lie straight or, as shown, 10 in a horizontal plane. The movement of the beam end will therefore be straight downward, and as the restraining links 16 and 17 break and move downwardly, the beam will float outwardly and its end continue to move downwardly. It will thus be seen that the post 9 rotates through 15 a controlled and predetermined arc governed by the links 16 and 17, the end of the beam which is connected to the polish rod 13 moving in a true vertical line. The same operation holds true 20 throughout the full upward and downward stroke of the beam 11.

A check may be made on the foregoing description of operation by referring to the diagram in 25 Fig. 4 in conjunction with the following trigonometric calculation:

Let α = any angular movement of walking beam

Then $D = L - L \cos \alpha$

And $D/2 = 2x - 2x \cos \alpha$

30 or $D = 4x - 4x \cos \alpha$

Therefore $x = L/4$ for any position and A moves in a true vertical line.

The foregoing calculation assumes that the 35 combined lengths of the links 16 and 17, or the distance between axes of 19 and 8, equals one-half the distance between the axes of 11a and 12 and that the pivotal axis of 19 lies midway between 10 and 11a.

40 It should be noted, however, that it is not necessary to locate pivot point 19 midway of pivot points 10 and 11a. If for any reason it should be desired to locate 19 nearer to 10, for example, than to 11a, links 16, 17 and 18 may be lengthened to compensate for such change. Accordingly D/2 becomes a variable factor and may be substituted by K. We then have:

$$D = L - L \cos \alpha = L (1 - \cos \alpha)$$

$$KD = 2x - 2x \cos \alpha = 2x (1 - \cos \alpha)$$

50 Then

$$K \cdot L (1 - \cos \alpha) = 2x (1 - \cos \alpha)$$

$$\text{and } K \cdot L = 2x$$

$$x = \frac{KL}{2}$$

55 It will be noted that the angle generated due to the angular travel of the walking beam is the same as that of the links 16 and 17, and that the respective lengths of the said links are the same. 60 Thus if the movable post 9 and links 16, 17 and 18 together with the walking beam 11 are initially set or arranged so that the said post lies in a true vertical plane, the polish rod connected to the one end of said beam must always be actuated in a plane whose axis lies parallel to the initial vertical axis of said post.

65 By checking the diagrammatic illustration in Fig. 4, it will be noted that the quadrilateral defined by the links 16 and 18 and the portions of the walking beam and movable post 9 which lie 70 between the pivotal points 21—11a and 11a—19 constitutes a parallelogram. Thus there are certain parts which must bear a definite or fixed relation to one another; pivot points 11a, 21 and 75 12 should lie in the same horizontal plane and 11a,

19 and 10 in the same vertical plane, and links 16 and 17 should be of the same length. However, the length of the floating Samson post 9 does not have to bear any definite or fixed relation to the length of the walking beam. Obviously, 5 the longer it is made, the less will be its deviation from a vertical plane while in operation. However, if the length of the post 9 is increased to too great an extent, manufacturing costs as well as transportation and assembly cost would be increased. For most practical purposes, the relative dimensions shown in the drawing will prove satisfactory.

10 In operation, the strain on the pivots or bearings of the links 16 and 17 increases in proportion to the deviation of said links. However, if the proportions illustrated in the drawing are substantially adhered to, the maximum deviation of the links 16 and 17 from a horizontal plane would be approximately fourteen degrees, which 20 has very little effect on the mechanical efficiency of the apparatus while in operation.

15 The arrangement herein disclosed is strong and rugged and may be adapted to both heavy duty and light service and yet at the same time, it is 25 simple in construction and involves relatively few moving parts.

20 It will also be noted that the horizontally extended frame structure having the linkage connected thereto in the manner shown braces the walking beam 11 against any tendency to swing or oscillate in a horizontal arc, thereby overcoming wobbling due to such action.

25 It will be readily understood that certain variations in structure and design may be adopted 35 within the scope of the invention as defined by the appended claims.

I claim:

1. In a pumping unit, a walking beam, a movable support providing a floating mounting for 40 said beam, a stationary upright frame for said support, and means for converting the arcuate movement of said beam into rectilinear movement at the pump-operating end thereof comprising linkage mechanism connected in toggle 45 relation on a common pivotal axis, said mechanism including opposed links arranged substantially horizontally with their ends remote from said axis pivoted respectively to the support and frame and an intermediate link having its remote end pivotally connected to the said beam. 50

2. In a pumping unit, a stationary support, a walking beam, a movable Samson post mounted on said support and providing a floating mounting for said beam, and means for converting the 55 arcuate movement of said beam into rectilinear movement at the pump-operating end thereof comprising linkage mechanism connected in toggle relation on a common pivotal axis, said mechanism including opposed horizontal links 60 having their ends remote from said axis pivoted respectively to the post and frame and an intermediate vertical link having its remote end pivotally connected to the said beam, said links being of such relative lengths that the angular travel 65 of the restraining links is the same as that of the walking beam.

3. In a pumping unit, a main stationary frame structure or Samson post, a movable Samson post pivotally mounted on said main Samson post, a 70 walking beam pivotally mounted on said movable Samson post, and means for converting the arcuate movement of said beam into rectilinear movement at the pump-operating end thereof comprising a plurality of restraining links connected 75

in T-shaped toggle relation, including opposed links pivotally connected respectively to the movable Samson post and the stationary Samson post and an intermediate link arranged substantially 5 perpendicularly to said opposed links and pivotally connected to said beam.

4. In a pumping unit, a main stationary Samson post, an arcuately movable Samson post pivotally mounted on said stationary Samson post, 10 a walking beam mounted on said movable Samson post for arcuate movement in a plane parallel to the plane of movement of said latter post, and means for converting the arcuate movement of said beam into rectilinear movement at the 15 pump-operating end thereof comprising a plurality of restraining links connected in toggle relation including opposed links arranged substantially horizontally, the outer end of one of the horizontal links being pivoted to said movable Samson post and the outer end of the other horizontal link being pivotally anchored to said stationary Samson post, and an intermediate link arranged substantially perpendicularly to the horizontal links and having its upper or outer 20 end pivotally connected to said beam.

5. In a pumping unit, a main stationary Samson post, an arcuately movable Samson post pivotally mounted on said stationary Samson post, a walking beam mounted on said movable Samson post for arcuate movement in a plane parallel to the plane of movement of said latter post, and means for converting the arcuate movement of said beam into rectilinear movement at the pump-operating end thereof comprising a plurality of restraining links connected in toggle 35 relation and including opposed links arranged substantially horizontally, the outer end of one of the horizontal links being pivoted to said movable Samson post and the outer end of the other horizontal link being pivotally anchored to said stationary Samson post, and an intermediate link arranged substantially perpendicularly to the horizontal links and having its upper or outer end pivotally connected to said beam, said opposed links being of substantially the same length.

6. In a pumping unit, a fixed Samson post, an arcuately movable Samson post mounted on the upper end of said fixed post, a walking beam pivotally mounted on said movable Samson post, a 50 pair of horizontal restraining links pivotally connected at their inner ends to a common axis and at their outer ends pivotally, respectively, to the fixed Samson post and the movable Samson post, and a third link arranged perpendicularly to horizontal links and having its lower end pivotally connected to said axis and its upper end connected to said beam.

7. In a pumping unit, a fixed Samson post, an arcuately movable Samson post mounted on the upper end of said fixed post, a walking beam pivotally mounted at an intermediate point on said movable Samson post, means operatively connected to one end of said beam for imparting a rocking movement thereto, the opposite end of said beam having an operative connection with the polish rod of a pump unit, and means for converting the arcuate movement of said beam into rectilinear movement at the point of its connection with the polish rod comprising a 65 plurality of restraining links connected in toggle relation on a common pivotal axis and including opposed links pivoted respectively at their outer ends to the movable Samson post and the fixed Samson post and an intermediate link pivotally 70 connected to said beam.

8. In a pumping unit, a fixed Samson post, an arcuately movable Samson post mounted on the upper end of said fixed post, a walking beam pivotally mounted at an intermediate point on said movable Samson post, means operatively 5 connected to one end of said beam for imparting a rocking movement thereto, the opposite end of said beam having an operative connection with the polish rod of a pump unit, and means for converting the arcuate movement of said beam 10 into rectilinear movement at the point of its connection with the polish rod comprising a plurality of restraining links connected in toggle relation on a common pivotal axis and including opposed links pivoted respectively at their outer ends to the movable Samson post and the fixed Samson post and an intermediate link pivotally 15 connected to said beam, said opposed links when in a neutral position lying in substantially a horizontal plane with the intermediate link arranged perpendicularly thereto.

9. In a pumping unit, a main stationary frame structure or Samson post, a movable Samson post pivotally mounted on said main Samson post, a walking beam pivotally mounted on said movable Samson post, and means for converting the arcuate movement of said beam into rectilinear movement at the pump operating end thereof comprising a plurality of restraining links connected in toggle relation, and including opposed links pivotally connected at their outer ends respectively to the main Samson post and the movable Samson post and an intermediate link pivotally connected at its upper end to said beam, a parallelogram being defined by the intermediate link, that portion of the walking beam which lies between its pivotal connection with the intermediate link and the movable Samson post, that portion of the Samson post which lies between its pivotal connection with the walking beam and the adjacent toggle link, and said latter link.

10. In a pumping unit, a main stationary frame structure or Samson post, a movable Samson post pivotally mounted at its lower end on said stationary Samson post, a walking beam pivotally mounted on the upper end of said movable Samson post, a plurality of restraining links connected in toggle relation including opposed links pivotally connected at their outer ends respectively to the stationary Samson post and the movable Samson post and an intermediate link pivotally connected at its upper end to said beam, and a polish rod having a pivotal connection with the pump operating end of said walking beam, 45 the pivotal connection of the upper ends of the movable Samson post, the intermediate link of the toggle and the polish rod lying in the same horizontal plane, and the pivotal connections of the movable Samson post with the walking beam, 55 the adjacent toggle link and the stationary Samson post lying in the same vertical plane.

11. In a pumping unit, a main stationary frame structure or Samson post, a movable Samson post pivotally mounted on said main Samson post, 65 a walking beam pivotally mounted on said movable Samson post, and means for converting the arcuate movement of said beam into rectilinear movement at the pump operating end thereof comprising a plurality of restraining links connected in toggle relation, and including opposed links pivotally connected at their outer ends respectively to the main Samson post and the movable Samson post and an intermediate link pivotally connected at its upper end to said beam, 70 75

the inner ends of all of said links being pivoted on a common axis, a parallelogram being defined by the intermediate link, the portion of the walking beam which lies between its pivotal connection with the intermediate link and the movable Samson post, that portion of the Samson post which lies between its pivotal connection with the

walking beam and the adjacent toggle link, and said latter link, and the pivotal connections of the movable Samson post with the walking beam, the adjacent toggle link and the stationary Samson post lying in the same vertical plane.

CHRISTOPHER G. HOPKINS.
